(57) **CLAIM**

The ornamental design for a mounting bracket, as shown and described.

DESCRIPTION

FIG. 1 is a perspective front view of a mounting bracket showing my new design;

FIG. 2 is a perspective top view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a front perspective view thereof, shown in an environment of use; and,

FIG. 10 is a front perspective view thereof, shown in an alternative environment of use.

The broken lines shown in the drawings are for illustrating portions of the mounting bracket that form no part of the claims design; Additional broken lines shown in FIGS. 9 and 10 are for purpose of illustrating environment subject matter only and form no part thereof.

1 Claim, 8 Drawing Sheets
